UNITED STATES PATENT OFFICE.

WILLIAM F. BOWERS, OF SAN FRANCISCO, CALIFORNIA.

DESIGN FOR A VEHICLE-TIRE.

47,873.

Specification for Design.

Patented Sept. 28, 1915.

Application filed August 10, 1915. Serial No. 44,831. Term of patent 14 years.

To all whom it may concern:

Be it known that I, WILLIAM F. BOWERS, a citizen of the United States, residing in the city and county of San Francisco, State of California, have invented a new, original, and ornamental Design for a Vehicle-Tire, of which the following is a specification, reference being had to the accompanying drawings, forming part thereof, wherein the figure is a view in plan of the tread of a tire, showing my new design.

I claim:—

The ornamental design for vehicle tire, as shown.

In witness whereof I have signed my name to this specification in the presence of two witnesses.

WILLIAM F. BOWERS.
